I. HECHENBLEIKNER ET AL.

METHOD OF AND APPARATUS FOR CONCENTRATING LIQUIDS

Filed June 26, 1922

Patented May 29, 1923.

1,456,874

UNITED STATES PATENT OFFICE.

INGENUIN HECHENBLEIKNER AND THOMAS C. OLIVER, OF CHARLOTTE, NORTH CAROLINA, ASSIGNORS TO CHEMICAL CONSTRUCTION COMPANY, OF NEW YORK, N. Y., A CORPORATION OF NORTH CAROLINA.

METHOD OF AND APPARATUS FOR CONCENTRATING LIQUIDS.

Application filed June 26, 1922. Serial No. 570,996.

To all whom it may concern:

Be it known that we, INGENUIN HECHENBLEIKNER and THOMAS C. OLIVER, citizens of the United States, and both residents of Charlotte, in the county of Mecklenburg and State of North Carolina, have invented certain new and useful Improvements in Methods of and Apparatus for Concentrating Liquids, of which the following is a

specification.

This invention relates to a method and apparatus for concentrating liquids such as sulphuric acid, and more particularly to a method and apparatus for concentrating sludge acids or separated sludge acids obtained in the refining of petroleum oils; and has special reference to the provision of an improved concentrator of the type in which hot gases are blown or discharged through the acid for effecting a concentration thereof.

One of the known methods of concentrating sulphuric acid, as disclosed for example in our prior Patent No. 1,415,443 of May 9, 1922 and in our copending application Ser. No. 477,936, filed June 16, 1921, consists in blowing or bubbling hot air or gases through a body of the acid for heating and agitating the same and effecting a concentration thereof below the true boiling point of the same. In this method the hot gases are conducted into a concentrating chamber and discharged into the body of acid therein below the surface thereof, the gases being injected and discharged into the

acid through a plurality of submerged pipes provided with spaced perforations. In the practice of this method and the use of this apparatus, the heat exchange between the hot gases and the acid, and therefore in a large measure the efficiency of the concentrating step, depends upon the depth of submergence of the perforated pipes in the body of acid. It is apparent that the deeper the submergence the longer is the time element

for a heat exchange between the acid and the hot gases issuing from the pipes; and in order to obtain a maximum heat exchange the pipes should be submerged a considerable depth below the level or surface of the acid in the compartment. This apparatus, however, where a maximum heat exchange is desired to be effected, has its limitations, since the depth of submergence of the perforated pipes can only be made relatively large at

the expense of too great a consumption of power employed in placing the hot gases under that pressure sufficient to drive the same through the deeply submerged pipe sections and into the acid. In increasing the depth of submergence, a point is reached where the power consumed in driving the hot gases against the pressure and resistance of the acid is excessive and greater than the economy obtained in the heat exchange, and therefore the pipes, where fuel economy is desired, cannot be submerged below a given depth. The perforated pipes are also relatively disadvantageous for the reason that resistance is met in the blowing of hot gases through the relatively small perforations therein, the perforations being moreover subject to liability of becoming plugged or stopped up by deposits in the concentrating chamber. To obviate these limitations and to remove the disadvantages inherent in and resulting from the employment of this method and apparatus are the principal objects of the present invention, the present invention comprehending an improved method and apparatus for concentrating the sulphuric acid whereby a relatively long and therefore greater heat exchange is obtained between the hot gases and the acid at a relatively small depth of submergence, an efficient heat exchange and acid concentration being therefore obtained without that consumption of energy incident to the prior method.

A further principal object of the present invention relates to a method of introducing the hot gases into the body of acid, whereby a circulatory motion is imparted to the acid while the hot gases are thoroughly comingled therewith, greater efficiency being obtained in the concentrating step.

The principal objects of the present invention may be said to include, besides the provision of an improved concentrator having the characteristics and capable of producing the results above mentioned, the further provision of a method and apparatus for discharging or injecting hot gases into a body of acid below the level thereof in such a manner that the hot gases are constrained to move through the body of acid a substantial horizontal distance at a relatively small depth of submergence, whereby a heat exchange is effected over a relatively long

path with a small energy consumption; the further provision of a method and apparatus of this nature in which one or more ducts or flues are provided in the concentrating chamber of the apparatus, the ducts or flues being so arranged therein as to lie below the normal acid level in the concentrating chamber, and in which the hot gases are introduced and injected into the said ducts or flues at 5 one end thereof and caused to move through the said duct and through the acid filling the same substantially the full length of the ducts; and the still further provision of an apparatus of this nature in which the ducts 10 are open at both ends and the hot gases introduced in such a manner as to effect a circulation of the acid through the said ducts while effecting an efficient comingling of the gases and the acid in the said ducts, concentration of the acid being obtained with great 15 economy and efficiency.

To the accomplishment of the foregoing and such other objects as will hereinafter appear, our invention consists in the elements and their relation one to the other, as hereinafter particularly described and sought to be defined in the claims, reference being had to the accompanying drawings which show a preferred embodiment of our 20 invention and in which:

Fig. 1 is a cross-sectional elevational view of the apparatus of our present invention,

Fig. 2 is an enlarged fragmentary view thereof,

Fig. 3 is a cross-sectional view of the same on the line 3—3, Fig. 2, and

Fig. 4 is a fragmentary view in cross-section on the line 4—4, Fig. 1.

In the carrying out of our process for 40 treating sludge acids or separated sludge acids, the acid is concentrated preferably in two stages, the acid being concentrated in the first stage up to an intermediate strength and thereafter treated in a second stage to 45 effect completion of concentration thereof. In each stage of operation a body of acid is collected in a chamber and hot gases such as hot air are introduced into the body of acid below the surface thereof, the heated 50 gases effecting an agitation and heating of the acid body or bath, effecting a concentration thereof. The spent gases issue from the bath and move through a tower of checker work into which is fed the weak sludge acid, 55 the said weak sludge acid running counter-current to the spent gases moving up the tower, the weak feed acid being preheated in this manner and fed into the body of acid for concentration. The method and apparatus 60 of our present invention is intended to be used or employed in both stages of treatment for concentration of the acid, and for purposes of illustration only one stage of concentration will be described, it being understood that the same process and apparatus 65

may be used for both stages or that the process and apparatus may be carried on merely in a single stage and may be used for the treatment of pure sulphuric acid as well as the sludge or separated sludge acid.

Referring to the drawings, the apparatus comprises a concentrating chamber C in which the body or bath of acid is concentrated, and a preheating tower T communicating with the concentrating chamber C, the spent gases issuing from the concentrating chamber having exit through the tower T, the said tower being employed for preheating a weak sludge acid fed into the same from the top thereof as will become clearer 70 hereinafter.

The concentrating chamber C comprises a trough-like flue provided with a bottom 10, side walls 11 and 12, and end walls 13 and 14 made of acid-proof brick laid in a suitable acid-proof mortar, a part of the said chamber being provided with an arched roof 15 also made of acid-proof material, the chamber being outwardly lined with lead, the lining forming a lead pan 16 covering the bottom, side and end walls of the chamber, the lead pan and concentrating chamber being suitably supported upon a cement foundation 17.

The tower T is built on the concentrating chamber C and comprises an elongated structure which may be about 30 feet in height and constructed of suitable acid-resisting brick, this tower being provided with a brick checker work 18 supported by a plurality of spaced arches 19, the roof of the tower being provided with an outlet flue 20 for the spent gases moving up the tower and with an inlet (not shown) through which the weak acid or the weak sludge acid is admitted into the tower. The roof may also be provided with a closed manhole 21. The tower T is used for preheating purposes; and where a sludge acid is fed down the tower counter-current to the spent gases moving upwards therethrough, the temperature of the tower is so regulated as to effect a preheating of the weak sludge acid sufficient to drive off the more volatile impurities therein. The tower T may also be provided at its bottom with a second manhole 22 for cleaning purposes.

For concentrating the acid in the chamber C, means is provided for conducting hot gases into and below the level of the acid bath, the gases being discharged into the acid for heating and agitating the same. As hereinbefore mentioned, the principal object of the present invention comprehends the provision of a method and apparatus in which the hot gases are introduced into the bath so as to obtain a long and efficient heat exchange at a relatively small depth of submergence, and therefore with a relatively low energy consumption. To effect these re- 130

sults the hot gases are injected horizontally into the acid bath and are caused to move a substantial horizontal distance at a relatively small depth of submergence, contact 5 between the hot gases and the acid being obtained over a horizontal path in contradistinction to a vertical path as is the case in prior methods. To accomplish these ends one or more ducts or flues are arranged in 10 the concentrating chamber C below the normal liquid level therein, so that the ducts or flues are normally filled with the acid to be concentrated, and heated gases are injected into these flues by means of pipes communicating 15 with the flues and extending part way therein, the construction being such that the gases are constrained to move throughout the length of the flues in contact with the acid filling the same. Referring now to 20 the drawings, this construction includes the subdivision of the concentrating chamber C by means of the spaced vertical walls 23 and the arched roofs 24 into a plurality of ducts or flues 25, these flues being arranged below 25 the normal liquid level 26 of the acid so that the acid normally fills the same. Communicating with each of the flues 25 there is provided a gas conducting pipe formed preferably of a vertical pipe section 30 30 connected for communication to a manifold 28 supported on a suitable structure 29 and a horizontal pipe section 30 connected to the vertical pipe section 27 by means of a packed joint 31 which may be of asbestos 35 rope soaked in thick acid-proof cement, each pipe section 30 extending part way and opening into a flue 25. The vertical pipe sections 27 are suitably sealed in the arched roof 15 of the concentrating chamber by 40 means of a block 32 and packing 33 of asbestos rope. The pipe sections 27 and 30 are of relatively large cross-sectional area, these pipes being for example about 10 inches in diameter. With this construction, the hot 45 gases are conducted from a source (not shown) through the manifold 28 and to and through the horizontally disposed pipe sections 30, the hot gases being injected into the flues 25, the said gases being constrained 50 by the said flues to move the full length thereof intimately intermixing with the acid therein. The operation is such that the acid is blown away by the hot gases from in front of the open pipe 30, and other acid immediately 55 rushes in from the rear to take its place, a succession of bubbles and liquid being thereby developed, and a circulation of the acid through the flue in the direction of gas flow and above the flue in the reverse 60 direction being thereby obtained, the flue open at both ends permitting an efficient agitation and circulation of the acid. With this construction therefore, a low depth of submergence may be resorted to, while a 65 relatively long path for the gases is pro- vided, a greater heat exchange with a given power consumption being obtained. Moreover, the large pipes employed offer less resistance to the flow of the gases and the large pipe openings present a minimum re- 70 sistance and permit lower power consumption in driving the gases through the concentrating bath. Furthermore, the large pipe openings are not so readily subject to becoming clogged up and pipe cleaning is more 75 easily effected. The brick flues provided afford a cheaper installation, this type of construction being moreover stronger and more rugged than the perforated pipes hitherto used. Another advantage of the brick 80 flue construction is that the length of the flue can be materially shortened as compared with the perforated pipes in prior constructions, with the result that a smaller concentrating chamber may be employed, effecting 85 a reduction in first cost and a saving of plant space.

For supporting the pipe sections 27 and 30 in the concentrating chamber, there are provided a plurality of spaced piers 34 one 90 for each of the vertical pipe sections, and a transversely arranged tie wall 35, the said tie wall being provided with a plurality of ports 36, the latter being provided for permitting the circulation of the acid in and 95 through the flues 25. The horizontal pipe sections 30 are further supported in the flue by means of the oppositely positioned pipe supports 37 and 38. For suitably bracing the arched roofs of the brick flues 100 against being lifted by the force of the heated gases, spaced walls 39 are provided for bracing the roofs 24 of the flues against the roof 15 of the concentrating chamber.

The concentrating chamber C is provided 105 with an acid collecting compartment 40 in which the concentrated acid collects for removal, the said collecting compartment 40 communicating with the concentrating compartment of the chamber C by way of a plurality of spaced ports 41, the concentrated acid collecting in the compartment 40 feeding into one or more coolers 42 through the conducting piping 43.

For the purpose of cleaning the pipe sections 30 to remove any deposits accumulating therein and over the openings thereof, the wall 14 of the concentrating chamber is provided with a plurality of cleaning openings 44, and each vertical pipe section 27 110 is provided with an orifice 45 arranged for registration with an opening 44, the construction being such that a suitable implement may be inserted through the opening 44 and orifice 45 and into the pipe section 120 30 for cleaning the same.

The manner of practicing the method and using the apparatus will in the main be apparent from the above detailed description thereof. The weak or dilute acid, such 125 130

for example as the separated sludge acid, is fed through the preheating tower T into the acid bath in the concentrating chamber C, heated gases under pressure being driven 5 through the conducting pipes 30 and injected into the acid below the surface thereof at a relatively small depth of submergence, the gases being injected into the flues 25 for movement therethrough and in 10 contact with the acid filling the same. The acid is thoroughly agitated by this treatment and a circulatory motion is imparted thereto, a heat exchange between the gases and the acid taking place over a considerable 15 horizontal path. The gases when leaving the flues 25 still have a vertical distance to travel, a long heat exchange being thereby effected. The spent gases issuing from the bath move up the preheating tower T and 20 out through the exit flue 20. The concentrated acid collects in the compartment 40 and feeds into the coolers 42 for further concentration or further use.

It will be apparent from the foregoing 25 that we have provided an improved air blown concentrator in which the concentration of the acid may be effected in a very efficient and economical manner, the concentrator being rugged and strong in construction and affording an economy in first cost, in plant space, and in operation. It 30 will be further apparent that the method and apparatus may be used for concentrating other liquids, and that the same may be used for effecting concentration of pure 35 as well as sludge acids, and that moreover the concentration may be effected in one or more stages. It will be further apparent that numerous constructional changes may 40 be made without departing from the spirit of the invention defined in the following claims.

We claim:

1. The method of concentrating liquids 45 which consists in injecting hot gases into a body of the liquid below the level thereof and in constraining the said hot gases to move in contact with the liquid over a substantial horizontal distance for effecting a 50 heat exchange between the gases and the liquid over a relatively long path.

2. The method of concentrating sulphuric acid which consists in discharging hot gases into a body of the acid below the level thereof 55 and in causing said gases to move in contact with the acid over a substantial horizontal distance for effecting a heat exchange between the gases and the acid at a relatively small depth of submergence and over 60 a relatively long path.

3. The method of concentrating liquids 65 which consists in filling a relatively long duct with the liquid, in injecting hot gases into the duct and discharging the same into the liquid filling the duct, with the hot gases

moving in contact with the liquid the length of the duct, whereby a heat exchange over a relatively long path and at a relatively small depth of submergence is effected.

4. The method of concentrating liquids 70 which consists in filling a horizontally arranged relatively long duct in a concentrating chamber with the liquid, in injecting and discharging hot gases into the duct at one end thereof, and in constraining the hot 75 gases to move through the duct and in contact with the liquid therein the length of the duct for effecting a heat exchange between the gases and the liquid over a relatively long path for concentrating the 80 liquid.

5. The method of concentrating liquids which consists in providing within a concentrating chamber a duct open at both ends and spaced from the top wall of the chamber, 85 in filling the duct with the liquid, in injecting hot gases into the duct at one end and causing the gases to move through the duct and in contact with the liquid, whereby a circulation of the liquid in and about the 90 duct and a concentration of the same is effected.

6. The method of concentrating sulphuric acid which consists in providing a concentrating chamber having a plurality of extended horizontally arranged flues therein, 95 in feeding a weak acid into the said chamber with the liquid level of the acid maintained therein above the said flues whereby the flues are normally filled with the acid, 100 and in injecting and discharging hot gases into the flues and the acid filling the same.

7. The method of concentrating liquids which consists in discharging hot gases into a body of the liquid below the level thereof, 105 in constraining the said hot gases to move through the liquid a substantial distance in a horizontal direction for effecting a heat exchange between the gases and the liquid over a relatively long horizontal path at a 110 relatively small depth of submergence.

8. An apparatus for concentrating liquids comprising a concentrating chamber adapted for holding a body of the liquid and means for discharging hot gases into the body of the liquid below the level thereof and for constraining the said hot gases to move in contact with the liquid over a substantial horizontal distance for effecting a heat exchange between the gases and the acid at a 115 relatively small depth of submergence and over a relatively long path.

9. An apparatus for concentrating sulphuric acid comprising a concentrating chamber adapted for holding a body of the acid, means for discharging hot gases into the body of the acid below the level thereof, and means for causing the said gases to move in contact with the acid a substantial distance in a horizontal direction for effecting 125 130

a heat exchange between the gases and the liquid over a relatively long path and at a relatively small depth of submergence.

10. An apparatus for concentrating sulfuric acid comprising a concentrating chamber adapted for holding a body of the acid, means for conducting hot gases into the body of the acid below the level thereof for discharge therein, means for causing the 10 said hot gases to move in contact with the acid over a substantial horizontal distance, the said means being constructed and arranged to effect a circulation of the acid in the said chamber and a concentration there- 15 of.

11. An apparatus for concentrating liquids comprising a concentrating chamber, a relatively long duct in said chamber arranged below the normal liquid level there- 20 in so that the liquid normally fills the same, and means for conducting and discharging hot gases into said duct for horizontal movement through the liquid filling the same for effecting a heat exchange between the gases 25 and the liquid over a relatively long path and at a relatively small depth of submergence.

12. An apparatus for concentrating liquids comprising a concentrating chamber, a relatively long duct in said chamber open 30 at both ends and arranged below the liquid level therein so that the liquid normally fills the said duct, and means for conducting hot gases into said duct for horizontal move- 35 ment through the liquid filling the same for effecting a heat exchange between the gases and the liquid over a relatively long path and at a relatively small depth of submergence.

40 13. An apparatus for concentrating sulfuric acid comprising a concentrating chamber, a flue disposed horizontally therein, the said flue being open at both ends and being arranged in the said chamber below 45 the normal acid level therein whereby the flue is normally filled with the acid, and means for injecting hot gases into the said flue and horizontally through the said acid, whereby a circulation of the acid through 50 and above the said flue and a heating and concentration thereof is effected.

14. An apparatus for concentrating liq-

uids comprising a concentrating chamber, a plurality of parallelly arranged flues in the said chamber, the said flues being each open 55 at both ends and arranged below the normal liquid level in the chamber, and means for injecting hot gases into the flues at one end thereof for effecting a circulation of the liquid through and above the flues and a heating and concentrating of the liquid therein.

15. An apparatus for concentrating liquids comprising a concentrating chamber, a preheating tower communicating therewith, a relatively extended duct in said chamber arranged below the liquid level therein with the liquid normally filling the same, means for feeding a weak acid into the said chamber through the said preheating tower, and 70 means for introducing hot gases into the said duct for horizontal movement through the liquid filling the same.

16. An apparatus for concentrating liquids comprising a concentrating chamber, a 75 duct in said chamber arranged below the liquid level therein with the liquid normally filling the same, and a second duct smaller than the said first duct and of relatively large cross-sectional area extending into the 80 said first duct at one end thereof and opening into the same and arranged for conducting hot gases into the said duct and through the liquid filling the same.

17. An apparatus for concentrating liquids comprising a concentrating chamber, a plurality of parallelly disposed flues in the said chamber, the said flues being open at both ends, a pipe communicating with each flue and extending part way into the same 85 at one end, the said pipe being adapted for conducting and injecting hot gases into the flue for effecting a circulation and concentration of the liquid filling the same.
